MARINE FLAGSTAFF

Donald J. Behnk, Pittsburgh, Pa., assignor to Attwood Brass Works, Inc., Grand Rapids, Mich., a corporation of Michigan

Application May 14, 1958, Serial No. 50,877

Term of patent 14 years

(Cl. D71—1)

Fig. 1 is a side elevational view of a marine flagstaff showing my new design.

Fig. 2 is a sectional view taken along the plane II—II of Fig. 1.

Fig. 3 is a rear-elevation view thereof.

I claim:

The ornamental design for a marine flagstaff, substantially as shown.
